UNITED STATES PATENT OFFICE.

JAMES TENNANT MCKEE, OF ST. JOHN, NEW BRUNSWICK, CANADA, ASSIGNOR OF ONE-THIRD TO THOMAS E. POWERS AND ONE-THIRD TO J. STARR TAIT, OF ST. JOHN, NEW BRUNSWICK, CANADA.

FUEL-SAVER.

1,086,834.

Specification of Letters Patent.

Patented Feb. 10, 1914.

Application filed December 23, 1912. Serial No. 738,342.

To all whom it may concern:

Be it known that I, JAMES TENNANT MCKEE, a subject of the King of Great Britain, residing at St. John, in the Province of New 5 Brunswick, Dominion of Canada, have invented certain new and useful Improvements in Fuel-Savers, of which the following is a specification.

This invention relates to fuel savers to be 10 used in connection with steam boilers, and the objects are to effect economy in fuel and to increase the power of the boiler.

Further objects are to generally simplify 15 and improve the construction so as to cause a complete combustion to be effected, to thoroughly heat the air which is introduced before it is discharged into the combustion chamber and to discharge the air at such point as will cause it to be of maximum efficiency, and it consists essentially of the improved construction hereinafter described in 20 detail in the accompanying specification and drawings.

In the drawings: Figure 1 represents a 25 front view partially in section illustrating a steam boiler and furnace embodying the present invention. Fig. 2 is a longitudinal section. Fig. 3 is a section on the line 2—2, Fig. 1.

30 Like characters of reference indicate corresponding parts in all the figures.

Referring to the drawings, A represents the boiler and B the masonry structure supporting the same, C represents the bridge 35 wall and D the grate bars and E the furnace. According to the present invention the bridge wall is made relatively thick and formed with four transverse passageways 10, 11, 12 and 13.

40 F represents an air inlet conduit which is embedded in the wall 15, is opened to the air at the front and connected at its inner extremity to one end of the conduit 11, the passageway 11 being placed in communication at the opposite end with the passageway 10 by means of a connecting passageway 16 and the passageway 10 being connected at the opposite end to an air outlet conduit G, also embedded in the masonry 45 in the wall 15 and turned across the forward part of the boiler in front of the door 17, provided with a downwardly inclined nozzle 18 in advance of the door, the pipe itself being embedded in the front wall 19, 50 the nozzle being located in the door opening

20. It will be seen that during the operation of the furnace air will be drawn in through the conduit F, passed successively through the passageways 11 and 10, be heated therein, then passed through the conduit 60 G and be discharged through the nozzle 18 onto the fire on the grates D to produce a secondary combustion and thereby increase the efficiency of the fuel. A second air inlet conduit H is provided on the opposite side 65 in the wall 21, said conduit communicating with the passageway 13 and the passageway 13 itself communicating at the opposite end with the passageway 12 by means of a connecting passageway 22, the opposite end of 70 the passageway 12 being connected with an air outlet conduit I, which ends in a nozzle 23 located within the space in front of the door 24 and adapted to discharge downwardly, the operation being similar to that 75 already described with respect to the first mentioned conduit.

J represents a third air inlet conduit which is embedded in the wall 15 and extends downwardly through the bridge wall 80 and is turned to discharge through a nozzle 25 directed toward the front of the grate bars and adapted to discharge in a direction substantially parallel with the surface thereof.

85 It will be observed that in the system of heating herein provided the air is in all cases supplied to the furnace in the temperature of the furnace and so no cold air comes in contact with the burning fuel. 90 There are also no openings through the furnace door, the hot air discharged into the interior being directed at a different angle and against the natural flow of the escaping gases will form a counter flow draft which 95 will increase the combustion.

As many changes could be made in the above construction and many apparently widely different embodiments of my invention, within the scope of the claim, constructed without departing from the spirit or scope thereof, it is intended that all matter contained in the accompanying specification and drawings shall be interpreted as 100 illustrative and not in a limiting sense.

105 What I claim as my invention is:

In a steam boiler furnace and in combination, a boiler, masonry structure supporting the same, a bridge wall, grate bars and furnace, said bridge wall being formed with 110

four transverse passageways 10, 11, 12 and 13, an air inlet conduit connected at its inner extremity to one end of the conduit 11, the conduit 11 being placed in communication at the opposite end with the passageway 10, an air outlet conduit connected to the opposite end of the passageway 10, said outlet conduit being turned across the forward part of the boiler in front of the door 10 thereof, an inclined nozzle on said last mentioned conduit in advance of the door, a second air inlet conduit communicating with the passageway 13, said passageway 13 communicating at the opposite end with the 15 passageway 12, a second air outlet conduit connected to the opposite end of the pas-

sageway 12, a nozzle forming a termination to said last mentioned air outlet conduit located within the space in front of the door and adapted to discharge downwardly 20 toward the bridge wall, and a third air inlet passageway extending forwardly from the front of the boiler and passing downwardly through the bridge wall and turned to discharge toward the front of the grate bars. 25

In witness whereof I have hereunto set my hand in the presence of two witnesses.

JAMES TENNANT McKEE.
